(57) **CLAIM**

I claim the ornamental design for a cord connector housing, as shown and described.

DESCRIPTION

FIG. 1 is a front right perspective view of a cord connector housing.

FIG. 2 is a front left perspective view of the cord connector housing of FIG. 1.

FIG. 3 is a top perspective view of the cord connector housing of FIG. 1; and,

FIG. 4 is a bottom perspective view of the cord connector housing of FIG. 1.
